MOTOR BIKE

David McElroy, St. Clair Shores, Mich., assignor to Engine Specialties, Inc., Cornwell Heights, Pa.

Filed Dec. 5, 1973, Ser. No. 422,054

Term of patent 14 years

Int. Cl. D12—11

U.S. Cl. D12—110

FIG. 1

FIG. 2

FIG. 3

Des. 241,241
Page 2 of 2

FIG. 4

FIG. 5

FIG. 1 is a right side elevation view of a motor bike showing my new design;

FIG. 2 is a left side elevation view thereof;

FIG. 3 is a top view thereof;

FIG. 4 is a front elevation view thereof; and

FIG. 5 is a rear elevation view thereof.

I claim:

The ornamental design for a motor bike, substantially as shown.
